DESIGN FOR A LAMP GUARD

Pansy E. Merrifield, St. Joseph, Mo., assignor to
Mary J. Coe, Kansas City, Mo.

Application April 27, 1938, Serial No. 76,761

Term of patent 14 years

To all whom it may concern:

Be it known that I, Pansy E. Merrifield, a citizen of the United States, residing at St. Joseph, in the county of Buchanan and State of Missouri, have invented a new, original, and ornamental Design for a Lamp Guard, of which the following is a specification, reference being had to the accompanying drawing, forming a part thereof.

Figure 1 is a side elevation of the lamp guard showing my new design; and

Fig. 2 is an end view of the same.

The ornamental features reside in the closure

which comprises a pair of kinked members extending across the end of the guard, the kinks of said members being V-shaped and in opposed relation. The kinks being to the outer side of the longitudinal axis of the member in which they are formed and all kinks of both members being in the same plane.

I claim:

The ornamental design for a lamp guard, as shown and described.

PANSY E. MERRIFIELD.
